UNITED STATES PATENT OFFICE

108,541

DESIGN FOR A WEDDING RING

Joseph Granat, San Francisco, Calif.

Application December 28, 1937, Serial No. 73,914

Term of patent 7 years

To all whom it may concern:

Be it known that I, Joseph Granat, a citizen of the United States of America, residing at San Francisco, in the county of San Francisco and State of California, have invented a new, original, and ornamental Design for a Wedding Ring, of which the following is a specification, reference being had to the accompanying drawing, forming a part thereof.

The figure is a perspective view of a wedding ring, showing my new design.

I claim:

The ornamental design for a wedding ring, substantially as shown.

JOSEPH GRANAT.
